B. L. SOUTHACK, OF NEW YORK, N. Y.

Letters Patent No. 83,333, dated October 20, 1868.

IMPROVED SOFA-BEDSTEAD.

The Schedule referred to in these Letters Patent and making part of the same.

To all whom it may concern:

Be it known that I, B. L. SOUTHACK, of New York, in the county of New York, and State of New York, have invented a new and useful Improvement in Sofa-Bedsteads; and I do hereby declare that the following is a full, clear, and exact description thereof, which will enable others skilled in the art to make and use the same, reference being had to the accompanying drawings, forming part of this specification, in which—

Figure 1 represents a vertical transverse section of my improved sofa-bedstead.

Figure 2 is a plan or top view, partly in section, of the same.

Similar letters of reference indicate like parts.

This invention relates to a new sofa-bedstead, which is provided with a folding back hinged to a sliding seat, the back, when turned up, resting against the back edge of the arm-rests or head-boards of the sofa, so as to be in a proper position.

The invention consists in such an arrangement of all parts, that the folding sofa-back, which is hinged to the sliding seat, and which forms, together with the seat, the bed-bottom, will, when turned up, bear or rest against the back edge of the arm-supports or head-boards, to which it may be secured.

A, in the drawing, represents the frame of my improved sofa-bedstead.

B B are the arm-supports or head-boards of the same.

The frame A may be of suitable size, shape, and material, and supported by suitable supports or standards C.

D is the seat of the sofa. It is made of slats, as shown, and upholstered or otherwise arranged in any suitable manner.

It is fitted with its ends into grooves a a, formed in the lower parts of the head-boards B, so that it can freely slide backward or forward on the sofa—backward, however, only to a certain limit, at least preferably.

E represents the back of the sofa. It is made also of slats, or in other suitable manner, and is, at its lower edge, by means of suitable hinges, b b, hinged to the back edge of the seat D, so that it may, when folded down, as shown by blue lines in fig. 1, be in line with and an extension of the said seat.

The back, when turned up, rests against the back end of the head-board B B, as in figs. 1 and 2, or against

tenons or arms projecting from the same, and is fastened to them by means of hooks and eyes c, or by other suitable equivalent apparatus.

By thus being fastened to the back end of the head-boards, the proper position of the seat and back on the sofa is readily ascertained and found.

To convert the sofa into a bedstead, the fastenings c are loosened, the back is folded down, as shown by blue lines in fig. 1, and then the whole seat, or rather bed-bottom, D E, is moved forward until the junction of the parts D E is about over the middle of the frame A. The bedstead is then ready. By having projecting ends, f, on the back, E, which may strike against the back ends of the head-boards, the proper position of the bed-bottom can also be readily ascertained.

I am aware that a sliding seat combined with a folding back of a sofa-bedstead is not new, it having been already used in the apparatus of John C. Emery, patented, June 10, 1848; but in that the back was constantly connected with the head-boards, by means of pivoted bars, which caused the motion of the back, when adjusted, to be constantly swinging, and thereby automatically produced the sliding motion of the seat.

It is evident that my device is considerably simpler and less complicated than the above, and that it can be produced at less cost; and the parts cannot so readily get out of order, no pivot-pins that might be strained being employed.

By having a bottom, d, on the frame A, and a folding lid e in front, or a drawer, a receptacle for bed-clothes or mattresses may be conveniently provided.

Having thus described my invention,

I claim as new, and desire to secure by Letters Patent—

The seat D, sliding in grooves a of the arm-rests B, and hinged at its rear edge to the back, E, which back is held up to the arm-rests B by the catches e and projections f, all operating as described, whereby the back is turned down into a horizontal position, and then drawn forward into the grooves a with the seat D, until arrested by the projection f, whereby a continuous bed-bottom is formed, as herein shown and described.

B. L. SOUTHACK.
